US0D1099905S

(12) **United States Design Patent** (10) **Patent No.:** **US D1,099,905 S**
(45) **Date of Patent:** **** Oct. 28, 2025**

(54) **TABLET PROTECTIVE CASE**

(71) Applicant: **Guangzhou Haichuan Technology Development Co., Ltd.**, Guangzhou (CN)

(72) Inventor: **Jinhua Cheng**, Guangzhou (CN)

(73) Assignee: **Guangzhou Haichuan Technology Development Co., Ltd.**, Guangzhou (CN)

(**) Term: **15 Years**

(21) Appl. No.: **29/934,708**

(22) Filed: **Mar. 27, 2024**

(30) **Foreign Application Priority Data**

Mar. 19, 2024 (CN) 202430142183.5

(51) **LOC (15) Cl.** **14-02**

(52) **U.S. Cl.** **D14/440**
USPC **D14/440**

(57) **CLAIM**

The ornamental design for a tablet protective case, as shown and described.

DESCRIPTION

FIG. 1 is a first perspective view of a tablet protective case showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is the using state of the tablet protective case thereof;

FIG. 10 is a front view of the opening state of the tablet protective case thereof;

FIG. 11 is a back view of the opening state of the tablet protective case thereof; and,

FIG. 12 is an enlarged view of the selected portion 12 in FIG. 1.

The broken lines shown in the drawings depict portions of the tablet protective case that form no part of the claimed design.

1 Claim, 12 Drawing Sheets
